APPARATUS FOR MAKING BROOMS

Henry Cave, Hartford, Conn., assignor to The Fuller Brush Company, Hartford, Conn., a corporation of Connecticut

Application August 5, 1940, Serial No. 351,448

4 Claims. (Cl. 300—12)

My invention relates to a process and apparatus for making brooms from various sorts of fibers and for assembling and securing the same in a very simple and efficient manner.

A machine embodying the invention and in the construction and use of which the objects herein set out, as well as others, may be attained is illustrated in the accompanying drawings, in which—

Figure 1 is a plan view of a portion of an apparatus embodying my invention and illustrating the method of forming a broom.

Figure 2 is a view in elevation of the apparatus shown in Fig. 1, Figs. 1 and 2 being of a diagrammatic character.

Figure 3 is an isometric view illustrating the holder embodying the invention and which is employed in practicing the process.

Figure 4 is a view similar to Fig. 3 and illustrating the manner of depositing broom fibers in the holder.

Figure 5 is another similar view illustrating the use of the holder in a further step in the process.

Figure 6 illustrates a still further step in the process employing the holder.

Figure 7 is a view illustrating the broom fibers finally clamped and secured in the holder.

Figure 8 is a view in section illustrating the construction and operation of the holder.

Figure 9 is a view in section on a plane denoted by the broken line 9—9 of Fig. 8.

Figure 10 is a detail view illustrating the tamping device.

In the accompanying drawings the numeral 10 denotes a carrier, preferably of circular form and rotatably mounted in any suitable manner within a stationary table 11, a portion only of which is shown in the drawings but which is located on different sides of the carrier and upon which broom material may be distributed and upon which holders may be manipulated in the making of brooms in a manner embodying the process in which the brooms are partially formed as hereinafter described. A fiber feeding device generally denoted by the numeral 12 is located in a position to deliver broom fibers to holders upon the carrier as the holders are moved along by the carrier underneath the feeding device that delivers the broom fibers into the holders. This fiber feed may be of old and well known construction commonly employed in the distribution of broom and brush fibers in the making of brooms and brushes, and as this in itself forms no part of the present invention a detailed description thereof will be omitted, it being sufficient to state

that it comprises a feed chute 13 in which the fibers are placed in horizontal positions and which may be urged downwardly by a weight 14 against the edge of a notched feed wheel 15 rotatably mounted in the bottom end of the chute and which may be rotated in the usual manner as by means of a motor 16, the broom material 17 in the form of fibers being picked up by the notches in the feed wheel and thereby carried through an outlet opening in the bottom of the chute from which they are deposited in the holders as the latter are carried underneath the opening by the operation of the carriers in a manner common to feed devices of this type.

15 A fiber holder, which as a whole is of U-shape, comprises a base 18 and upstanding ends 19—20 which are curved or beveled at their outer ends as at 21 for the purpose of ready reception of a clamp bar 22. Each of the upstanding ends has 20 a hole 23 and one end may have a groove 24 leading into the hole therein, as shown in Fig. 3. The base 18 may be provided with positioning notches 25—26 on opposite edges thereof to receive positioning lugs 27—28 relatively fixed in and projecting from the carrier 10 to locate the holders in proper positions on the carrier end to end and preferably against or in close proximity to each other as shown in Fig. 2.

The clamping bars 22 are each provided with 30 a retaining pin or pins 29 projecting from one or both ends to engage in one or both of the holes 23, these pins being spring pressed outwardly. Finger pins 30 projecting from each of the retaining pins through slots in the edges of the bar 35 serve as a means for disengaging the retaining pins from the holes in the ends of the holders. Abutments 31 are fixed on the table in position to receive the ends of the broom fibers 17 carried by the holders, there being an abutment appurtenant to each set of positioning lugs on the carriers.

In the practice of the process an operative at station A places holders successively in position on the carrier in engagement with the positioning lugs, with the ends of the holders preferably in contact, as shown in Fig. 1. From this station the holders are moved by the carrier to station B where each receives a layer 32 of broom material deposited therein by operation of the fiber feed 12. From station B the holders with the layer 32 of fibers therein pass to station C where a second layer 33 of fibers is placed upon the first layer in each of the holders. This second layer of fibers may be different in character, as to quality, coarseness, or otherwise, from the

first layer, this constituting a core of the broom, and in common practice this second layer 33 is manually arranged upon the table 11 by an operative and then placed upon the first layer. While this is common practice at the present time, it is contemplated that this second layer may be placed in the holders by the operation of a fiber feed apparatus as at station B, and the process is not therefore to be limited to the manner of depositing this second layer or core of 10 fibers at the station C.

From station C the holders with the two layers 32-33 of fibers therein journey to station D, where a third layer 34 of fibers is placed upon the layer 33, this layer 34 of fibers being preferably of the same character as the layer 32. This third layer 34 is preferably deposited in the holders by the operation of the feed device 35 in substantially the same manner as at station B by the fiber feed 12.

From station D the holders pass by operation of the carrier to station E where an operative places the clamping bars 22 successively within the holders as they approach this station, as shown in Figs. 1 and 6. In this operation one of the retaining pins 29 is thrust into its companion hole 23 in the upstanding end 19 of the holder and the retaining pin at the opposite end of the bar is engaged in the groove 24 in the upstanding end 20, and by means of a handle 37 on a clamp operating lever 36 pivotally mounted on the structure at the end opposite the handle and as shown in the center of the table 11 the clamp engaging pin 38, see Fig. 6, is thrust against the side of the bar 22 and the retaining pin 29 at this end of the bar is forced along the groove 24 into position where it snaps into the hole 23 in the upstanding end 20 of the holder.

From station E the holders with the several layers of broom material therein are passed to station F and underneath a tamping device generally denoted by the numeral 39. This tamping device may be of any suitable character and only a brief description thereof will be given herein. Thus stated this device consists of a case 40 within which a shaft 41 from a motor 42 extends, said shaft having laterally extending arms forming cranks 45 operatively connected with tamping fingers 43 located on opposite sides of the clamp and as shown in Figs. 1 and 10, which fingers, as the shaft is rotated by the motor 42, exert a rapid tamping action upon the broom material within the holder as the material is passed underneath the ends of said fingers. This tamping operation firmly sets the material in a closely compacted state within the holder.

From this compacting station F the holders pass to station A where the operative successively removes the holders and places them in a chain carrier 44 in an upended position, as shown in Fig. 1, and by which carrier they are transported through a vat (not shown) containing an adhesive mixture, the ends only of the fibers being dipped into the mixture. After treatment with the adhesive the holders are removed from the fiber mass in subsequent operations which include the fastening of metallic plates to secure the fibers and form the broom head, a description of these operations being omitted herein as not comprising a feature of this invention.

In accordance with the provisions of the pat-

ent statutes I have described the principles of operation of my invention, together with the device which I now consider to represent the best embodiment thereof; but I desire to have it understood that the device shown is only illustrative and that the invention may be carried out by other means and applied to uses other than those above set out within the scope of the claims.

I claim:

1. A holder comprising a separate article adapted for expeditious and ready handling in a process for making brooms, said holder comprising a base in the form of a narrow, single piece of material having upstanding ends of substantially equal lengths with a clear space for the full length of said base between said ends, a clamping bar of a length substantially that of the space between said ends adapted to be placed between said ends and removably attached to said base, and means for unobstructed interlocking engagement of the opposite ends of said bar with said upstanding ends upon presentation of said bar ends into locking relationship with said upstanding ends.

2. A holder comprising a separate article adapted for expeditious and ready handling in a process for making brooms, said holder comprising a base in the form of a narrow, single piece of material having upstanding ends of sub-

stantially equal lengths with a clear space for the full length of the base between said ends, a clamping bar of a length substantially that of the space between said ends adapted to be placed between said ends and removably attached to said base, and means for unobstructed interlocking engagement of the opposite ends of said bar with said upstanding ends upon presentation of said bar ends into locking relationship with said upstanding ends.

3. A holder comprising a base in the form of a narrow, single piece of material having upstanding ends of substantially equal lengths with a clear space for the full length of the base between said ends, a clamping bar of a length substantially that of the space between said ends adapted to be placed between said ends and removably attached to said base, and means for unobstructed interlocking engagement of the opposite ends of said bar with said upstanding ends upon presentation of said bar ends into locking relationship with said upstanding ends, one of said means including a pin on the bar insertable into a fixedly positioned hole in an upstanding end and the other means including a latching engagement of the end of the bar with an upstanding end.

4. A holder for use in a process for making brooms, said holder comprising a base in the form of a narrow, single, undivided piece having upstanding ends of equal length with a clear space for the full length of the base between said ends, a clamping bar of a length substantially that of the space between said upstanding ends, a pin secured to one end of the clamping bar to engage a hole in an upstanding end, and a pin loosely mounted in the opposite end of the clamping bar for engagement in a hole in the other upstanding end.

5. A holder for use in a process for making brooms, said holder comprising a base in the form of a narrow, single, undivided piece having upstanding ends of equal length with a clear space for the full length of the base between said ends, each of said upstanding ends having a hole near its upper end and one of said ends having a guide slot intersecting the hole there-

6. A holder for use in a process for making brooms, said holder comprising a base in the form of a narrow, single, undivided piece having upstanding ends of equal length with a clear space for the full length of the base between said ends, each of said upstanding ends having a hole near its upper end and one of said ends having a guide slot intersecting the hole there- 70 in, a clamping bar of a length substantially that of the space between said upstanding ends, a pin on one end of the clamping bar to engage a hole in one upstanding end, and a pin slidably mounted in the opposite end of the clamping bar to engage within said groove for guidance into said hole to removably secure this end of the bar in place.

HENRY CAVE.
